UNITED STATES PATENT OFFICE.

WILLIAM GOLDIE, JR., OF BAY CITY, MICHIGAN.

SPIKE AND TIE-PLATE.

No. 884,578

Specification of Letters Patent.

Patented April 14, 1908.

Application filed May 6, 1907. Serial No. 372,116.

To all whom it may concern:

Be it known that I, WILLIAM GOLDIE, Jr., a resident of Bay City, in the county of Bay and State of Michigan, have invented a new and useful Improvement in Spikes and Tie-Plates; and I do hereby declare the following to be a full, clear, and exact description thereof.

My invention relates to tie plates, its object being to provide a simple and efficient means for holding an ordinary flat faced tie plate, which is the cheapest form of tie plate made, to the tie, and thus reduce the cost of manufacture as compared with tie plates having prongs formed integral therewith. In such integral pronged tie plate the cost of manufacture has been excessive, first, on account of the peculiar shape of the plate to be rolled, and further on account of the great waste of metal because continuous flanges must be rolled on the under surface of the plate and these flanges cut out to form the prongs and the prongs subsequently sharpened. It has also been found impracticable to form the prongs any distance in from the side edges, on account of the difficulty of rolling and the difficulty of sharpening the prongs though a prong located directly under the rail will obtain a stronger and firmer hold. The present invention has advantages over such construction, as hereafter set forth.

It consists in a tie plate having one or more grooves extending across its upper face and a slot or slots extending down from the groove or grooves through the plate, and a tie pin adapted to be driven through the slot into the tie and provided with a head which is seated within the groove and held in place therein by the rail, the pin head corresponding in shape to the groove and filling the same.

In the accompanying drawings Figure 1 is a perspective view of the tie plate; Fig. 2, is a like view of the tie pin; Fig. 3 is a side view of the tie pin; and Fig. 4 is a cross section of a rail and tie plate illustrating the use of the invention.

In the accompanying drawing the rail 1 rests upon the tie plate 2 which in turn rests on the tie 3. The tie plate preferably has the shoulder 4 rolled thereon to receive the lateral thrust of the rail and it is also provided on its upper face with the one or more grooves 5 which, as shown, extend longitudinally of the rail parallel to the shoulder 4. Plates of this section can be rapidly and

cheaply rolled, and to complete them requires only the cutting of the plates to length, the punching of the spike hole 6 therein and punching in the groove or grooves 5 of one or more pin holes 7 according to the number of pins desired for holding the tie plate to the tie. The tie pin 8 employed has the body portion 9, which has the tapering point 10 provided with the cutting edges 11, it being preferred that these tie pins shall be made thin and wide so as to obtain a wide bearing upon the plate itself and upon the tie into which they are driven in order to resist lateral thrust of the rail upon the tie plate. These tie pins have above the body portion the heads 12 which correspond in shape to the grooves 5 in the upper face of the tie plate so that when the pins are driven to place they are seated entirely within that groove and they also fill the groove so as to close the same and resist any tendency to buckling in the plate on account of the thinning thereof in the formation of the groove. These tie pins can be very cheaply and rapidly made by rolling a bar of the section shown and cutting the same to the desired width of pin and then shearing the pin diagonally in the direction of its length to form the cutting edges.

In the use of the invention the tie plates are set upon the tie, being spaced to give the exact gage required, and the pins, one or more, are driven through the pin holes in the bottom of the plates, being driven down so that their heads are fully seated within the longitudinal groove or grooves 5 of the plate so securing the plate to the tie. After the rail has been placed upon the tie plate it is spiked to the tie in the usual way and as it rests directly upon the tie pins 8 it holds the same in place, so binding the tie plate to the tie by the weight of the rail and the passing train. As the hold of the tie plate upon the tie is independent of the spikes, and directly under the rail, a much firmer hold is obtained than in the case of prongs which are set out beyond the portion of the tie plate on which the rail bears. These pins can also be made of greater length than the ordinary prong integral with the plate, and better cutting edges can be obtained on them, so that a much firmer hold of the tie plate to the tie is obtained. As the pin heads 12 when driven to place fill the grooves 5, it is evident that they resist any possible tendency to bending or buckling of the plate.

in carrying the load on the rail. Consequently, an exceedingly strong, simple and cheap tie plate construction is thus provided.

What I claim is:

1. In combination with the rail and tie, a tie plate having a groove extending across its upper face and within the bearing surface covered by the rail, a slot extending down from the groove through the plate, and a tie pin adapted to be driven through the slot into the tie and having its head seated in the groove in the plate.
2. In combination with the rail and tie, a tie plate having a groove extending across its upper face, a slot extending down from the groove through the plate, and a tie pin adapted to be driven through the slot into.

the tie and having its head seated in the groove in the tie plate.

3. The combination with a rail and tie, a tie plate having a groove extending across its upper face, a slot extending down from the groove through the plate, and a tie pin adapted to be driven through the slot into the tie and having its head corresponding in size to the groove in the tie and filling the same.

In testimony whereof, I, the said WILLIAM GOLDIE, Jr., have hereunto set my hand.

WILLIAM GOLDIE, JUNR.
